UNITED STATES PATENT OFFICE

ERWIN HARRIS OAKMAN, OF ATLANTA, GEORGIA

SANITARY BASE FOR TABLE LEGS, ETC.

Application filed March 19, 1928. Serial No. 262,707.

This invention aims to provide a simple but effective means whereby ants and bugs will be prevented from creeping from the floor upon the legs of tables and food cabinets, 5 or bedsteads and to produce a device for this purpose suitable to support the legs of furniture either with or without casters.

It is within the province of the disclosure to improve generally and to enhance the 10 utility of devices of that type to which the invention appertains.

With the above and other objects in view, which will appear as the description proceeds, the invention resides in the combination and arrangement of parts and in the 15 details of construction hereinafter described and claimed, it being understood that changes in the precise embodiment of the invention herein disclosed may be made within the 20 scope of what is claimed, without departing from the spirit of the invention.

In the accompanying drawings:—

Figure 1 shows in vertical section, a device constructed in accordance with the invention, 25 the leg of the article of furniture appearing in elevation;

Figure 2 is a plan of the device which forms the subject matter of this application;

Figure 3 is a section on the line 3—3 of 30 Figure 1;

Figure 4 is a sectional elevation showing the modification;

Figure 5 is a section on the line 5—5 of 35 Figure 4.

In carrying out the invention, there is provided a receptacle 1, including a base 2 and an upstanding rim 3. A tubular bearing 4 is mounted on the base 2, within the rim 3. The numeral 5 marks the cover having a disk-like depending reinforcement 6 from which 40 projects a spindle 7. The spindle 7 is journaled for rotation in the bearing 4, and the disk-like part 6 rests on the upper end of the bearing 4. In the upper surface of the 45 cover 5 there is a seat 8, preferably of elongated trough-like form, as shown in Figure 2, the seat being adapted to receive the 50 caster 9 on the leg 10 of a bed or other article of furniture, the surface of the cover 5 on each side of the seat 8 being aligned horizon-

tally to support furniture legs without casters.

In practical operation, an insecticide is placed in the receptacle 1 and insects cannot pass up from the floor upon the leg 10 of the furniture. The construction is such that there is ample room between the cover 5 and the upper edge of the rim 3 and thus the insecticide can be placed in the receptacle 1 by means of a spoon or otherwise, without taking the device out from under the leg of the furniture. In placing the device under the leg of the furniture, the cover may be revolved to bring the seat in position to receive the caster. 55 60 65

In Figure 3, the receptacle is shown as being circular in outline, but it may be of any other shape. Thus, Figure 5 shows the receptacle as being rectangular in outline. In Figures 4 and 5, parts hereinbefore described 70 have been designated by numerals previously used with the suffix "a". In this form of the invention, there is a reversal of parts in that the spindle 7^a is on the base 2^a of the receptacle 1^a, the tubular bearing 4^a being connected to the part 6^a of the cover 5^a. 75

What is claimed is:

In a sanitary base for furniture: a basin for holding insecticide having a bottom and an elevated rim, a plate extending horizontally straight across and above the top of the rim and the basin, the upper side of the plate having a shallow elongated groove in its surface, the upper surface of the plate surrounding the groove being flat, the outer portion of the under side of the plate being flat, the central portion having a disk-like depending reinforcement forming a bed for the groove, the plate being spaced from the rim and supported by a member located between the reinforcement and the inner portion of the bottom. 80 85 90 95

In testimony that I claim the foregoing as my own, I have hereto affixed my signature.

ERWIN HARRIS OAKMAN.
